UNITED STATES PATENT OFFICE.

FRANK DUTCHER, OF VERSAILLES, PENNSYLVANIA, ASSIGNOR TO CENTRAL RAILWAY SIGNAL COMPANY, OF PITTSBURGH, PENNSYLVANIA, A CORPORATION OF NEW JERSEY.

RAILWAY SIGNAL-TORPEDO.

1,137,588.

Specification of Letters Patent. Patented Apr. 27, 1915.

Application filed December 9, 1913. Serial No. 805,620.

To all whom it may concern:

Be it known that I, FRANK DUTCHER, citizen of the United States, residing at Versailles, in the county of Allegheny and State 5 of Pennsylvania, have invented certain new and useful Improvements in Railway Signal-Torpedoes, of which the following is a specification, reference being had therein to the accompanying drawing.

10 This invention relates to improvements in railway signal torpedoes and which pertains to a torpedo made from a blank sheet of paper having the central portion depressed to form a recess to receive the explosive charge, the central portion having side and end flaps to fold inward and over each other to form an inclosure for the explosive charge within the recess.

15 The primary object of my present invention is to have the inturned flaps hold a rail-engaging strap to the torpedo, by means of which strap the torpedo is fastened to the railroad-rail.

20 A further object of my present invention is to strengthen the paper case and to have the inturned flaps unite a rail-engaging strap to the torpedo for holding the torpedo to the railway-rail.

25 In the accompanying drawings—Figure 1 is a perspective view of my improved torpedo in which a spring rail-engaging strap is shown attached thereto. Fig. 2 is a sectional view of the line 2—2 of Fig. 1. Fig. 3 is a sectional view of the line 3—3 of Fig. 35 2. Fig. 4 is a perspective view of the several parts comprising the torpedo, the parts being shown in separated relation. Fig. 5 is an inverted perspective view showing a modification for attaching a lead rail-engaging strap to the torpedo.

40 Referring now to the drawings and particularly to Fig. 4 the paper or fiber case is made from a paper blank A having a central portion 1, and this central portion is 45 bulged outward to form a recess 2 to receive the explosive compound 3 which is preferably in the form of a tablet as shown in Fig. 4. This central portion 1, is provided with end flaps 4 and with side flaps 5. The side flaps 5 are turned in over the explosive compound and in order to permit these to be folded in properly, there are provided the U-shaped folds 6 formed in the corners of the main or body portion 1, and these U-shaped folds extend inward at an angle and

gradually decrease toward their inner end until they disappear at the wall of the recess 2.

When a spring rail-engaging strap 7 is to be used, then a plate 8 is provided, and this plate is located between the folded in side flaps 5 and the folded end flaps 4. The spring strap 7 is attached to this plate 8, preferably by a rivet 9. The plate 8 is cemented on top of the folded side flaps 5, 65 and the folded in end flaps 4 are cemented to the outside of the plate 8. This cement is made of a water-proof compound preferably and will serve ordinarily to unite the flaps to the plate and hold the plate in place 70 which carries the rail-engaging strap. However to further insure the attachment of the plate to the torpedo case especially when a spring strap is used, the corners of the plate are provided with ears or lugs 9, are 75 turned around over the end flaps 4 and serve to insure holding the end flaps closed and the plate in position. Attention is also directed to the fact that these ears being located at the corners of the plate they can 80 be firmly and tightly closed against the end flaps because there is no explosive compound, at the corners of the torpedo, owing to the oval or round-shape of the recess 2 which forms the flat corners 10 (see Fig. 1) 85 under which the ears 9 are turned and tightly clamped.

When a lead strap is used, there is no appreciable strain on the torpedo case when the strap is being opened up or folded 90 around the railway-rail, and when the lead strap is used the plate 8 may be omitted as shown in Fig. 5. In this event, however, the end flaps 4 will be sufficiently long to substantially meet in the center of the lead 95 strap 11 as shown at 12, and the side flaps, end flaps, and strap will be cemented together.

The particular advantage of this torpedo resides in the fact that the recess 2 can be 100 made of the oval wedge-shaped form here shown, or the recess can be made round. Both of these shapes are familiar to the railroads in metal torpedoes and have proven highly successful.

105 I am aware that it is not new to form a torpedo from a blank having side and end flaps and the central portion having a recess to receive an explosive compound, but this type of torpedo, so far as I am aware, has 110

never been manufactured and sold because no practical way has been found to attach either a lead or a spring strap thereto.

By the construction herein shown I provide a torpedo, the case of which consists of a non-flying fiber which will not injure persons who happen to be near when the torpedo is exploded by a passing train, and one which is so constructed that either a lead strap or a spring strap can be practically, cheaply and efficiently attached to the case.

Having thus described my invention what I claim and desire to secure by Letters Patent is:

1. An improved torpedo comprising a case made of a fibrous blank having a central portion provided with an explosive receiving recess, the blank having inwardly folding flaps, a plate located between the flaps, a strap connected to the plate, the said plate provided with ears turned over and clamping the outer inturned flap to the plate for the purpose described.
2. An improved torpedo, comprising a case made of a paper blank, having a central portion provided with an explosive receiving recess, the side and end flaps folded inward, a plate located between the side and end flaps, the plate and flaps cemented to-

gether, a strap connected to the plate, the plate provided with ears turned over and clamping the outer inturned flaps to the plate for the purpose described.

3. An improved torpedo, comprising a case made of a paper blank having a central portion provided with an explosive receiving recess, the central portion having inturned side flaps and inturned end flaps, a plate located between the side and end flaps, the flaps and plate cemented together, the corners of the plate having ears turned inward on the outer side of the outer inturned flaps for clamping the parts together.

4. An improved torpedo comprising a case made of a fibrous blank having a central portion provided with an explosive receiving recess, the central portion having inwardly folded flaps, a plate located between the said flaps, a strap connected to the plate, the corners of the plate provided with ears turned over and clamping one of the inturned flaps to the plate for the purpose described.

In testimony whereof I hereunto affix my signature in the presence of two witnesses.

FRANK DUTCHER.
